UNITED STATES PATENT OFFICE.

WILLIAM P. ISRAEL, OF NEW YORK, N. Y., ASSIGNOR TO RAYMOND C. PENFIELD, OF NEW YORK, N. Y.

BRICK LIFTING AND TRANSFERRING MECHANISM.

1,134,953.

Specification of Letters Patent.

Patented Apr. 6, 1915.

Application filed July 17, 1911. Serial No. 638,969.

To all whom it may concern:

Be it known that I, WILLIAM P. ISRAEL, a citizen of the United States, and resident of New York city, county and State of New York, have invented an Improvement in Brick Lifting and Transferring Mechanisms, of which the following description, in connection with the accompanying drawings, is a specification, like letters on the drawings representing like parts.

This invention relates to the handling of bricks in units of considerable size and is adapted for use either for lifting and transporting burned bricks from the kiln to a transfer point, or from a transfer point to any desired place of delivery, and also for the handling of green bricks in the process of manufacture, either in close or open formation. When used for handling burned bricks *en masse* as for delivery to the point of destination for use, the apparatus is also adapted to serve as a means of counting the bricks as it comprises a cage, which, when filled either completely or to a definite extent, will hold a definite number of bricks.

The invention consists in a lifting frame which is preferably, though not necessarily, in the form of an inclosing cage adapted to be set down over the stack of bricks to be lifted, and in combination therewith a set of lifting rods or bars to be raised by said frame adapted to engage underneath the stack for lifting the same, and having provision to laterally engage and frictionally grip the lower-most layer of bricks in the stack, which, for this purpose, is arranged in spaced apart lines, the spaces between the lines serving for the introduction of the lifting bars.

The invention will be more fully understood from the following detailed description taken in connection with the accompanying drawings, and is hereafter set forth in the appended claims.

Referring to the drawings: Figure 1 is a vertical section through the apparatus in a direction lengthwise of the lifting bars and showing one of said bars in elevation. Fig. 2 is a fragmentary detail end elevation looking from the left in Fig. 1. Fig. 3 is a fragmentary horizontal sectional view through one of the lifting bars. Fig. 4 is a fragmentary elevation showing a portion of one of the lifting bars. Fig. 5 is a plan of one of

the lifting bars removed, a line of bricks being shown in dotted lines to illustrate the manner of gripping the same, and Fig. 6 is an enlarged detail end elevation further showing the manner of frictionally gripping the bricks of the bottom lines.

The framework 10 may be of any suitable construction and is preferably formed as a rectangular openwork cage having top horizontal bars 11 to which lifting straps 12 may be fixed. The cage shown has a series of vertical bars or plates 13 fixed to the top horizontal bars 11 and these may be suitably secured together at their bottoms by other horizontal bars 14, the whole constituting the rectangular sides of a cage open at its bottom and preferably of a size to fit a stack composed of some definite number of bricks in a predetermined stacked form. Along two opposite sides of the cage so formed near its bottom are fixed clips 15, 16, the clip 15 having an inturned ledge 17 inclined slightly upward and the clip 16 at the opposite side having a similar slightly upturned ledge 18 projecting outward therefrom.

These ledges are for the purpose of receiving and holding the ends of a set of lifting bars 19, these bars having at their forward ends slightly downturned projections 20 adapted to interengage with the ledge 17 and at their rear ends brackets 21 with inturned ends which may be slightly bent downward to securely interlock with the upwardly bent ledges 18. The several lifting bars are similar in construction and each consists of two bar members 22, 23, preferably of angle iron and shown as L-shaped in cross section and held in parallelism or slightly converging toward their outer ends and with their inner vertical sides spaced apart approximately the width of a brick or a little farther and held in this relation by being fixed at their rear ends to a stiff strong plate 24 which may be a part of the bracket 21. The bar members 22, 23 are so fixed to the plate 24 that their horizontal flanges 25, 26 extend oppositely outward at the top of the lifting bar structure thus formed. A suitable handle 27 may be fixed to each lifting bar at its rear end, being as shown, suitably fixed to the plate 24. The inner vertical sides or flanges of the bar elements 22, 23 have a series of slots 28 formed therein at frequent intervals, in practice about three inches

apart, and through these slots disks 29 are made to project, being journaled at 30 on springs 31 which are fixed at 32 to the vertical sides of the bars and these springs press the disks 29 with some little force through the slots 28 into the space between the lifting bar elements 22, 23.

Referring to Fig. 4 it will be noted that the disks 29 laterally fit the slots 28 quite closely so that the walls of said slots furnish a guiding support for the disks. It may now be understood that a pile of bricks having been formed with the bottom layer in separated lines with spaces between lines sufficient to permit the lifting bars as described to be inserted and the rest of the pile being laid thereover, the cage 10 may be lowered over the pile, and, when rested on the ground or other support of the stacked pile, the lifting bars may be slid through the bottom of the stack each bar straddling with its two sides one of the bottom brick lines and being pushed forward until the projections 20 at its forward end engage over the inturned ledge 17, the inturned end of the bracket 21 at the same time engaging over the ledge 18 at the rear end. As the lifting bars are thus pushed into place the laterally arranged disks 29, which are adapted to turn on their axes to constitute anti-friction devices, are forced outward against the pressure of the springs 31 and so continue to press upon the sides of the bricks with some little force and enough to lift them with the stack. This arrangement of the disks 29, whereby they constitute anti-friction devices in the lengthwise movement of the lifting bars into place so as to permit the bars to be easily inserted, and their serving thereafter as friction grippers to insure the lifting of the bottom brick lines by reason of the spring mounting of their axes, I consider a most important feature of the invention and as I believe the same to be broadly new I desire to cover this construction without limitation as to specific details. As the disks 29 are spaced as described, about three inches apart, it is apparent that at least two of these disks will grip each side of each brick so that every brick is gripped at a plurality of separated points on each side and the line is lifted in undisturbed formation.

In practice the bar elements 22, 23 are about one and one-half inches in cross section each way, so as to be readily insertible in a space provided by the bottom lines of bricks laid flatwise as shown. The forward ends of these bars may have their vertical flanges tapered or beveled off as seen at 33 to facilitate the pushing of the bars into place, and the horizontal top flanges extend beyond the ends of the vertical flanges to form the projections 20. These projections

20 may likewise have their opposite inner extremities beveled as seen at 34 to facilitate the insertion of the same past the bricks. After the load is transferred to the desired destination it may be set down and the lifting bars withdrawn without disturbing the spaced apart line formation of the bottom of the pile so that the pile may be again lifted by the lifting apparatus described or any other type of mechanical lifter with lifting devices insertible in spaces in the bottom of the stack.

It is to be observed that the described apparatus is adapted to handle the pile of bricks and transport the same to the desired destination without disturbing the stacked formation, or any rough treatment whatever which would be apt to break or chip off the corners of the bricks; further that bricks may be handled very rapidly in large quantities and that if required the measurement of the amount handled may very easily be made by reference to the known capacity of the cage or basket. While the apparatus may be advantageously employed for handling and transferring finished burned brick in the course of transportation to the point of use, by reason of the particularly careful and gentle handling of the bricks the mechanism is also well adapted for use in transferring green bricks to the drier or dried bricks to the kiln for burning in the process of manufacture.

It is to be understood that the apparatus is susceptible of considerable variation without departing from the spirit of the invention. For example, while the framework of the carrier is shown as a cage 10, this is merely illustrative since in the broader aspects of the invention the essential parts of such framework are the opposite spaced apart side lifting elements 15, 16 adapted to be let down over opposite sides of the pile. The lifting bars shown for interengagement with these side lifting elements are likewise to be understood merely as typifying any suitable lifting devices adapted for interengagement with such side lifting elements, these bars being preferably individually insertible through the pile to engage the lifting frame and also preferably having self-acting devices adapted to permit the bars to be readily inserted and without manipulation to then exert an effective friction grip upon the bottom brick lines to lift the same.

Thus it is to be noted that the specific construction of these lifting bars likewise may be varied within considerable limits without departing from the invention, and I desire this term in the claims to be understood in a generic sense, except when otherwise limited. I therefore do not desire to be limited to the exact construction shown in any of these particulars, in any way except as pointed out in the appended claims.

While the apparatus has been described as for the handling of bricks, it is to be understood that this particular application of the invention is merely illustrative and that the mechanism is likewise adapted for handling other kinds of merchandise or material composed of articles of definite form adapted to be arranged in stacked piles. I therefore desire to cover the apparatus for use 10 in handling such material generally.

Having described my invention, what I claim as new and desire to secure by Letters Patent is as follows:

1. An apparatus of the kind described, 15 comprising an open-bottomed lifting frame adapted to be positioned adjacent a pile of brick, a plurality of bars to form a removable bottom for said frame, each bar carrying anti-friction brick engaging devices 20 to lift a foundation row of the pile and being adapted to support the superposed pile on top of the bars, said frame having on opposite sides thereof means integral therewith to engage with co-operating engaging 25 devices on opposite ends of each bar, whereby the removable bottom bars and frame are automatically connected when the frame is lifted and are automatically disconnected when the apparatus is lowered to the 30 ground.

2. An apparatus of the kind described, 35 comprising an open-bottomed lifting frame adapted to be positioned adjacent a pile of brick, a plurality of bars to form a removable bottom for said frame, each bar carrying anti-friction brick engaging devices to straddle a foundation row and adapted to support the superposed pile on top of the bars, in combination with automatically 40 acting connections from the opposite ends of each bar with the adjacent opposite sides of the frame, to connect and lift said bars when the frame is lifted, each of said automatic connecting devices on the bars and 45 frame being normally out of contact when said bars are positioned under the brick pile, whereby the frame may be lifted instantly after positioning the bars and the bars may be instantly removed after the 50 frame is lowered to the ground.

3. An apparatus of the kind described, 55 comprising a lifting frame having portions adapted to be let down over opposite sides of a pile of bricks to the lower part thereof, lifting bars adapted for insertion through spaces in the bottom of the brick pile and to engage said frame portions to be lifted thereby, and means fixedly mounted on said lifting bars for exerting a self-acting grip 60 upon the sides of the bottom brick lines as said bars are inserted in place, said means being formed to yield on engagement with a brick line and arranged for an anti-friction engagement with the bricks as the bars are moved into place.

4. An apparatus of the kind described, 70 comprising a lifting frame having portions adapted to be let down over opposite sides of a pile of bricks, lifting bars adapted for insertion through spaces at the bottom of the brick pile to engage said lifting frame, and means directly carried by said lifting bars mounted and arranged for a self-acting anti-friction engagement with the bottom brick lines as the bars are moved into 75 place and then for a self-acting frictional grip upon the bricks to lift the same.

5. An apparatus of the kind described, 80 comprising a frame adapted to be let down over opposite sides of a pile of bricks, lifting bars adapted for insertion through spaces in the bottom of the brick pile to engage said frame at opposite sides of the pile, and disks having spring 85 mountings on vertical axes at intervals along said bars and arranged to be pressed by the bricks as the bars are inserted and to thereafter exert a friction grip thereon to lift the same.

6. An apparatus of the kind described, 90 comprising a frame having portions adapted to be disposed at opposite sides of the lower portion of a brick pile, and lifting bars adapted for insertion through spaces in the bottom of the pile and to engage said frame 95 portions, each of said bars being composed of a pair of spaced apart bar elements secured together at one end, with devices projecting into the space therebetween adapted to exert a yielding pressure upon a brick 100 line in said space permitting longitudinal insertion of the bar along said line and to exert a substantial friction grip upon the bricks to lift the same vertically.

7. An apparatus of the kind described, 105 comprising a lifting frame having portions adapted to extend along opposite sides of a brick pile, and a plurality of lifting devices adapted to be individually inserted through spaces in the bottom of the brick pile to 110 engage said frame portions and to engage the bottom lines of brick to lift the same with the stack, each of said devices having portions to extend along at opposite sides of a brick line with provision to engage the 115 same for lifting it.

8. An apparatus of the kind described, 120 comprising a lifting frame having portions adapted to extend along opposite sides of a brick pile, and a set of lifting devices individually insertible through the bottom of the brick stack to engage said frame portions, each of said lifting devices having bar members to extend along at opposite sides of a brick line and provided with self-acting means for exerting a lifting grip thereon.

9. In an apparatus of the kind described, 125 a lifting bar composed of a pair of angle irons rigidly fixed together at one end in 130

spaced apart relation to receive between them a brick line, and a series of disks mounted along said bar elements to yield horizontally but rigidly supported vertically, said disks being adapted to yieldingly grip the brick line as the bar is inserted and to frictionally hold the bricks for lifting the same.

10. In an apparatus for transporting
bricks and similar articles, the combination
of a carrier having an open bottom, with a
plurality of individually insertible and re-
movable lifting bars forming the bottom of
the carrier, each lifting bar comprising a
15 pair of members spaced rigidly apart a dis-
tance slightly greater than the width of the
articles to be lifted, and immovable with
respect to each other, and a plurality of
20 gripping elements spaced apart longitudi-
nally on the members and tensioned in-
wardly to grip opposite sides of the articles.

11. In an apparatus for carrying bricks
or the like, the combination of a carrier
having an open bottom, with a plurality of
25 individually insertible and removable lift-
ing bars forming the bottom of the carrier,
each lifting bar consisting of spaced parallel
members connected together at one end
30 of the bar and free from each other
throughout the remainder of their length,
said members being relatively immovable
and each member having a plurality of
35 spaced slots, and gripping devices fastened
to the members and extending through the
slots to grip opposite sides of the bricks
disposed between the members.

12. In an apparatus for carrying bricks
or the like, a lifting bar consisting of
spaced parallel members connected together
40 at only one end of the bar and free from
each other throughout the remainder of
their length and each having a plurality of
spaced slots, gripping devices fastened to
45 the members and extending through the
slots to grip opposite sides of the bricks
disposed between the members, each device
comprising a roller extending through the
slot, and a spring compressing the roller
50 inwardly.

50. 13. In an apparatus for carrying bricks
or the like, a lifting bar composed of spaced
members with oppositely-disposed slots, a
roller mounted in each slot, and a leaf
55 spring fastened to the outer face of each
bar for supporting each roller normally
pressing the latter inwardly so that oppo-
site rollers are spaced apart a distance less
than the width of the bricks to be carried.

14. In an apparatus for carrying bricks
60 or the like, a lifting bar comprising rigidly
spaced members, a plurality of springs
mounted on each member and spaced longi-
tudinally apart, rollers mounted on the
springs, the rollers of one member being
65 oppositely disposed to the rollers on the

other member and spaced from each other
transversely of the bar a distance less than
the width of the bricks, and spaced from
each other longitudinally of the bar a dis-
tance less than the length of a brick where-
70 by a plurality of rollers of each member
will engage a single brick.

15. In an apparatus for carrying bricks
or the like, the combination of a carrier
having an open bottom, with a plurality of
75 individually insertible and removable lift-
ing bars forming the bottom of the carrier,
each lifting bar comprising spaced parallel
members free from each other at one end
80 of the bar, a member forming a connector
rigidly uniting the other ends of the mem-
bers together to form the sole means for
holding them in spaced relation, and means
mounted on the said parallel members for
gripping the bricks. 85

16. In an apparatus for carrying bricks
or the like, the combination of a carrier hav-
ing an open bottom, with a plurality of in-
dividually insertible and removable lifting
90 bars forming the bottom of the carrier, each
lifting bar comprising spaced parallel mem-
bers free from each other at one end of the
bar, a member forming a connector rigidly
95 uniting the other ends of the members to-
gether to form the sole means for holding
them in spaced relation, means mounted on
the said parallel members for gripping the
bricks, and a handle on the connector. 95

17. In an apparatus for carrying bricks
or the like, a lifting bar comprising spaced
parallel members free from each other at
100 one end of the bar, a member forming a con-
nector rigidly uniting the other ends of the
members together to form the sole means
for holding them in spaced relation, means
105 mounted on the said parallel members for
gripping the bricks, means on the connector
for attaching one end of the bar to a car-
rier, and means on the unconnected ends
110 of the said parallel members for attaching
the opposite ends of the bar to the carrier.

18. A lifting bar comprising a pair of
spaced members, an angle iron to which the
extremities of the members at one end of the
bar are rigidly connected, a handle on the
115 angle iron, a flange on the angle iron for
hooking one end of the bar on a carrier,
and devices on the other extremities of the
members for engaging the bar with the car-
rier. 120

19. A lifting bar of the class described
comprising a pair of parallel members
formed of angle irons, a connector for rig-
idly connecting the members together at one
end and forming the sole means for holding
125 the members spaced apart, means on the con-
nector for detachably engaging the bar with
a carrier, means on the unconnected ends
of the members opposite from the connector
for detachably engaging the bar with the 130

carrier, and gripping devices mounted on each member and tensioned inwardly toward the devices on the opposite member.

20. The combination of a carrier having at one side an outwardly-extending horizontal flange and at the opposite side an inwardly-extending horizontal flange, and a plurality of lifting bars having devices at their ends for detachably engaging with the flanges.

21. The combination of a carrier having at one side an outwardly-extending horizontal flange and at the opposite side an inwardly-extending horizontal flange, a plurality of lifting bars having devices at their ends for detachably engaging with the flanges, and a handle on one end of each lifting bar.

22. The combination of a carrier, horizontal flanges at opposite sides thereof adjacent the bottom, a plurality of lifting bars, devices on the ends of the bars for detachably interlocking with the said flanges, each bar consisting of a U-shaped structure including side members, and gripping devices spaced apart longitudinally on the side members, the devices of each member being tensioned inwardly toward and disposed opposite the devices of the opposite member.

23. The combination of a carrier in the form of a rigid structure open at its bottom and having the bottom edge of its front wall located above the plane of the bottom edges of the other walls, a plurality of lifting bars insertible into and removable from the structure under the bottom edge of the front wall, and means on the structure with which the ends of the lifting bars removable engage.

24. The combination of a carrier in the

form of a rigid structure open at its bottom and having the bottom edge of its front wall located above the plane of the bottom edges of the other walls, a plurality of lifting bars insertible into and removable from the structure under the bottom edge of the front wall, an internal flange on the rear wall of the structure with which the inner ends of the lifting bars engage, and an external flange on the front wall of the structure with which the front ends of the lifting bars engage.

25. The combination of a carrier, internal and external flanges on the rear and front walls of the carrier respectively, the external flange being located at a higher level than the internal flange, lifting bars extending across the bottom of the structure with their rear ends removably engaging and supported by the internal flange, and means carried by the front ends of the bar for removably engaging the external flange.

26. The combination of a carrier having horizontal flanges at its front and rear walls, the front flange being located at a higher level than the rear flange, and lifting bars having means at their extremities for engaging the flanges to be supported thereby, the side walls of the carrier extending downwardly along the sides of the outermost lifting bars for preventing lateral displacement of such bars from the flanges.

In testimony whereof, I have signed my name to this specification, in the presence of two subscribing witnesses.

WILLIAM P. ISRAEL.
